DENTAL FLOSS HOLDER

Dona B. Recchia and Peter L. Recchia, Los Angeles, Calif.
(both of 19121 Clymer St., Northridge, Calif. 91324)

Filed Dec. 10, 1973, Ser. No. 423,439

Term of patent 14 years

Int. Cl. D24—99

U.S. Cl. D24—1 D

FIG. 1 is a top plan view of a dental floss holder, showing our new design; the bottom, not shown, is the mirror image of the top;

FIG. 2 is a side view thereof; and

FIG. 3 is an enlarged perspective view thereof.

We claim:

The ornamental design for a dental floss holder, substantially as shown and described.
